US00D564326S

(12) **United States Design Patent** (10) **Patent No.:** **US D564,326 S**
(45) **Date of Patent:** **** Mar. 18, 2008**

(54) **FOLDING MULTIPURPOSE HAND TOOL**

(75) Inventors: **Hollan Akio Tsuda**, Portland, OR (US);
Blair Scott Barnes, Portland, OR (US);
Charles F. Goodrich, Vancouver, WA (US); **Melissa C. Yale**, Portland, OR (US); **Nathan E. Knight**, Portland, OR (US)

(73) Assignee: **Leatherman Tool Group, Inc.**,
Portland, OR (US)

(**) Term: **14 Years**

(21) Appl. No.: **29/249,426**

(22) Filed: **Oct. 5, 2006**

(57) **CLAIM**

The ornamental design for a folding multipurpose hand tool, as shown and described.

DESCRIPTION

FIG. 1 is a perspective view of the top plan, left side elevation, and rear elevation views of a folding multipurpose hand tool according to an embodiment of the present invention;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is another right side elevation view thereof, shown with a gut hook portion in an extended position;

FIG. 9 is yet another right side elevation view thereof, shown with a knife portion and a gut hook portion in folded positions;

FIG. 10 is a perspective view of the top plan, left side elevation, and rear elevation views of a folding multipurpose hand tool according to another embodiment of the present invention;

FIG. 11 is a right side elevation view thereof;

FIG. 12 is a left side elevation view thereof;

FIG. 13 is a top plan view thereof;

FIG. 14 is a bottom plan view thereof;

FIG. 15 is a front elevation view thereof;

FIG. 16 is a rear elevation view thereof;

FIG. 17 is another right side elevation view thereof, shown with a gut hook portion in an extended position; and,

FIG. 18 is yet another right side elevation view thereof, shown with a knife portion and a gut hook portion in folded positions.

The broken lines shown herein are for illustrative purposes only and form no part of the claimed design.
